UNITED STATES PATENT OFFICE.

MAURICE RATEL, OF PARIS, FRANCE.

MECHANICAL FURNACE OF THE UNDERFEED TYPE.

1,366,098.

Specification of Letters Patent. Patented Jan. 18, 1921.

Original application filed March 28, 1913, Serial No. 757,353. Divided and this application filed March 30, 1914. Serial No. 828,423.

To all whom it may concern:

Be it known that I, MAURICE RATEL, a citizen of the French Republic, and resident of Paris, France, have invented certain new and useful Improvements in Mechanical Furnaces of the Underfeed Type.

This invention relates to automatic stokers, and more particularly to stokers of the underfeed type, and has for its object to provide an improved device of this character.

Automatic stokers of the underfeed type heretofore employed have been more or less defective in their manner of distributing the fuel and cleaning the furnace. Where fixed plates or bars have been used for the grate, there is produced at the center a thick bed of burning fuel into which the air penetrates with difficulty and wherein the carbon dioxide produced in the neighborhood of the twyers is reduced to carbon monoxide in passing through the incandescent fuel and, owing to the lack of sufficient air, escapes without combustion and with the consequent loss of heat. Furthermore, this type of furnace requires hand cleaning and therefore, imposes heavy labor on the fireman. To obviate the disadvantages of this type of furnace it has been suggested to effect distribution of the fuel and cleaning of the grate by movement of the bars in a variety of ways. Such movable grate bars, operating by shearing action on the fuel, are effective to a greater or less extent in breaking up and moving the body of incandescent fuel; but they are quickly burned out because surrounded on three of their faces with incandescent fuel for at least a part of the time.

To avoid the defects incident to this type of grate it has been suggested to effect the feeding of the fuel and cleaning of the grate by inclining the grate so that the movement of the fuel and solid products of combustion is effected with the aid of gravity. In view of the relatively steep angle of repose possessed by the ordinary fuels, however, this type of grate requires considerable height whereby it is unavailable for use with locomotive or marine boilers or stationary boilers where a relatively high grate cannot be had.

It has also been suggested to provide an inclined grate with one or more fuel retorts or troughs which intersect the grate

and to feed the fuel to the grate through said retorts or troughs by fuel feeding devices in each of them. Furnaces of this type heretofore constructed have not been entirely satisfactory, however, because with the available inclination of grate there has been a bad distribution of fuel and imperfect combustion arising from the uneven supply of air to the incandescent fuel. The angle of repose of the fuel being much greater than the angle of the grate, the fuel has had a tendency to collect in a thick bed at the upper part of the grate and, the air penetrating this thick bed with difficulty, there has been an insufficient supply of air at this portion of the fuel bed with a resultant formation of carbon monoxide which escapes without combustion and with a consequent loss of heat. Also, owing to the tendency of the ashes and fuel to fuse large lumps are formed which tend to take a steeper angle of repose until, becoming detached, they produce a sudden movement of the fuel and solid products of combustion in the nature of an avalanche, which carries with it both fuel and solid products of combustion onto the dumping sections of the grate. Much of this fuel is smothered in the ashes and slag so that it is carried into the ash pit and becomes lost. Furthermore, when the fuel is fed at the same rate through the bottom of the retorts as at the top of the retorts, much fuel is pushed directly from the retorts onto the dumping grate where it is buried in the ashes and slag, and becomes extinguished and lost.

It is the object of the present invention to overcome these defects and disadvantages by providing a proper distribution of the fuel to the fuel bed and causing a continuous and regular advancing movement of the entire fuel bed by feeding successively decreasing quantities of fuel to the successive portions of the main grate as it inclines toward the dumping grate, as by use of fuel feeding devices of successively decreasing stroke, or by use of fuel feeding devices having the same stroke but of successively decreasing capacity, or by both.

A further object of the invention is to provide, in combination with fuel feeding devices of the type last referred to, a receiving grate at the foot of the incline of the main grate, said receiving grate preferably comprising a plurality of movable grate bars,

the same desirably having movement in reverse directions in the same plane, so that they will act like a sifter and insure a regular advancement of the fuel bed.

- 5 Another object of the invention is to provide a mechanical furnace as heretofore described wherein the bars of the receiving grate are provided with an air supply which diminishes in quantity toward the dumping 10 grate and which in the rearmost bars may be replaced by an injection of steam to form combustible gases by coming in contact with the incandescent solid products of combustion.
- 15 Another object of the invention is to obviate the difficulties heretofore experienced from the rapid burning of the twyers by so constructing them that the air flowing through the same comes into cooling contact 20 with the heated surfaces or that the ashes tend to form protective layers on their exterior surfaces, or both; or, in combination therewith, said twyers may be further cooled by the injection of steam, humid air, water 25 spray or circulating water. Furthermore, to obviate the difficulty heretofore experienced from the rapid burning of the dumping grate, the same or a similar construction may be applied thereto.
- 30 A further object of the invention is to provide, in combination with a mechanical furnace of the type heretofore described, means for varying the rate at which the fuel and air is supplied thereto, even though only a 35 constant speed motor is available, said means preferably permitting of automatic variation and control.

- Other objects relate to the provision of a mechanical furnace of the type referred to 40 which is simple in construction, efficient in operation, inexpensive to maintain, and economical in its use of fuel.

The invention is capable of receiving a variety of mechanical expressions, some of 45 which are shown on the accompanying drawings, but it is to be expressly understood that the drawings are for purposes of illustration only and are not to be construed as a definition of the limits of the invention, 50 reference being had to the appended claims for that purpose.

In said drawings, Figure 1 is a vertical section through a trough or retort of a mechanical furnace employing an under- 55 feed stoker which embodies the present invention.

Fig. 2 is a transverse section of the furnace shown in Fig. 1.

Fig. 3 is a section of twyers embodying 60 the present invention.

Fig. 4 is a plan view of the twyers of Fig. 3.

Figs. 5 and 6 are sections of other forms of twyers embodying the present invention.

65 Fig. 7 is a diagrammatic view of means

for varying the working of the furnace when a constant speed motor is employed; and

Fig. 8 is a schematic view of means for individually varying the speed of each 70 stoker and automatically controlling the admission of air.

The present invention is capable of application to a wide variety of boilers and forms of furnaces and, therefore, as it is not 75 limited to any particular type of boiler or furnace construction, the details of the latter have not been illustrated.

In the embodiment of the invention shown in Fig. 1, a construction of grate is employed 80 which is particularly suitable for use with marine and locomotive boilers. The main grate is composed of a series of twyers 37 of any suitable construction successively decreasing in elevation from a medial fore and 85 aft line toward the sides of the furnace so as to provide a grate of the gravity feed type, said twyers being separated by fuel retorts or troughs 34, 35, 36, etc., at and on both sides of said medial line. Said troughs or 90 retorts are shown as of successively decreasing depth but they may be of the same or of successively decreasing cross section. The fuel is supplied the grate, from the hopper 81, in progressively decreasing quantities 95 from said medial line toward the sides of the furnace by fuel feeding devices of progressively decreasing stroke or capacity in the successive retorts or troughs. The said fuel pushers may be of any suitable construction, being shown as of successively decreasing capacity toward the sides of the 100 furnace and each comprising a main piston or pusher 82, actuated in any suitable way as by crank mechanism from the shaft 22, 105 and a plurality of secondary pushers 83 connected thereto by the rod 86, the succeeding pushers in each trough also being of successively decreasing capacity from the front 110 to the rear of the grate. Receiving grates composed of movable bars 38, 39, 40, etc., desirably having reverse movement in the same plane, are preferably positioned at each side of the furnace at the base of the inclines of the main grate, and said grate bars may be 115 provided with an air-supply progressively decreasing toward the dumping grate, as diagrammatically illustrated by the decreasing size of the air passages 84 in said bars. Air is supplied said twyers and bars in any 120 suitable way. A dumping grate 41 is also shown at the outer side of each of said receiving grates.

The twyers are preferably so constructed 125 that their surfaces are maintained relatively cool. To this end they may be provided with external grooves 42 in which the ashes collect to form a heat-protecting layer, as shown in Figs. 3 and 4; or they may be provided interiorly with partitions 31 for di- 130

recting the incoming air into cooling contact with their surfaces, as shown in Fig. 5; or they may be provided with said partitions 31 and have their surfaces corrugated to 5 form external recesses in which the ashes collect to form a protective layer, as shown in Fig. 6. Said twyers may be of any suitable form and cross section and they may be built up in any suitable way.

10 Any suitable means may be provided for driving the stoker and varying its speed. In the form shown, shaft 22 is driven from shaft 19 through the belt or chain drive 20 and speed reducing mechanism of any suitable 15 construction, said shaft 19 in turn being driven from any suitable source of power. When a steam engine or direct current motor is employed the speed may be varied automatically or otherwise in any suitable way, 20 as by automatically controlled valves or an automatically controlled rheostat. When an alternating current is used however, and particularly when a three phase current is employed so that only slight variations of 25 speed may be obtained by variation of the current, change speed devices of any suitable construction may be applied to the fan and stokers and also individually to each stoker to secure the proper regulation of the speed.

30 As diagrammatically illustrated in Fig. 7, the main shaft 19 may be driven from the driving shaft 43 of a constant speed motor 44 through suitable gearing 48. A clutch is diagrammatically illustrated at 45 and the fan or blower at 47, said fan and main shaft 19 being driven from the shaft 43, upon actuation of the clutch 45, through a change speed box 46 of any suitable construction. In addition to the mechanism just described 40 for varying the speed of the entire stoker and blower, a change speed box may be provided for each individual stoker as shown diagrammatically in Fig. 8, wherein 49 is the change speed box, 50 is a gear driven 45 in any suitable way from the main shaft 19, and 51 is a clutch of any suitable construction for connecting the gear 50 with the driving shaft of the change speed mechanism in the box 49, said clutch being normally pressed into operative position by the 50 spring 54. The change speed mechanism is shown as controlled by a lever 55 having a handle 56 which controls a catch for engagement with the teeth 58 of the sector plate 85. Said lever 56 may have an extension 57 for engagement with the arm 53 of the bell crank 52, 53, which in turn controls the movement of the clutch 51 into and out of 55 operative position.

60 It is also desirable that the mechanism for changing the speed of each stoker be connected to the damper for admitting air to the furnace so as to maintain a constant relation between the quantity of fuel and the 65 quantity of air supplied to the furnace.

This is accomplished in the structure diagrammatically illustrated in Fig. 8 by the connection of the damper 60 with the lever 55 by a cable 59, a counterweight 62 being shown as connected to the arm 61 of the 70 damper 60 to facilitate adjustment of the latter.

While the constructions shown on the drawings have been described with considerable particularity it is to be expressly understood that the invention is not limited thereto, as the same is capable of being embodied in a variety of forms. In place of the types of fuel feeding devices shown, any other suitable fuel feeding means for feeding progressively decreasing quantities of fuel may be employed. The number, form and inclination of the twyers and the number and size of the fuel retorts or troughs may also be varied in conformity with the fuel to be 75 employed. It is also to be understood that reference to the twyers as successively decreasing in elevation refers only to the relation of their fuel-supporting surfaces to a base line, without limitation as to the size, 80 shape or cross section of the twyers themselves. Furthermore, while the invention has been shown as embodied in a furnace wherein air is supplied to the grate by a fan or blower it is to be understood that it is 85 within the contemplation of this invention to use a natural draft when such is available. Reference is therefore to be had to the claims hereto appended for a definition of 90 the limits of the invention.

100 This application is a division of my application Sr. No. 757,353 filed March 28, 1913 and is directed more particularly to one embodiment of the generic invention, other embodiments and generic features of 105 construction being claimed both generically and specifically in the original and other divisional applications.

What is claimed is:—

1. In an automatic underfeed stoker, a 110 series of twyers successively decreasing in elevation from a medial fore and aft line toward the sides of the furnace, fuel retorts or troughs at and on both sides of said medial line, and means for feeding fuel 115 through said retorts or troughs to said twyers.

2. In an automatic underfeed stoker, a series of twyers successively decreasing in elevation from a medial fore and aft line 120 toward the sides of the furnace, fuel retorts or troughs at and on both sides of said medial line, and means for feeding progressively smaller quantities of fuel through the successive retorts or troughs on each side of 125 said medial line.

3. In an automatic underfeed stoker, a series of twyers successively decreasing in elevation from a medial fore and aft line 130 toward the sides of the furnace, fuel retorts

or troughs at and on both sides of said medial line, and a fuel pusher reciprocatory in each of said troughs or retorts for feeding fuel through said retorts or troughs to 5 said twyers.

4. In an automatic underfeed stoker, a series of twyers successively decreasing in elevation from a medial fore and aft line toward the sides of the furnace, fuel retorts or troughs at and on both sides of said medial line, and fuel feeding devices successively decreasing in size for feeding progressively smaller quantities of fuel through the successive retorts or troughs on each 10 side of said medial line.

5. In an automatic underfeed stoker, a series of twyers successively decreasing in elevation from a medial fore and aft line toward the sides of the furnace, fuel retorts or troughs at and on both sides of said medial line, and fuel feeding means in said retorts or troughs for feeding a progressively diminishing quantity of fuel along each retort or trough. 20

6. In an underfeed stoker, a plurality of twyers successively decreasing in elevation from an intermediate line toward the sides of the furnace whereby the fuel and solid products of combustion are fed by 30 gravity from an intermediate portion toward the sides of the furnace, and means for feeding fuel to said twyers at said intermediate line and on both sides thereof.

7. In an underfeed stoker, a plurality of twyers successively decreasing in elevation from an intermediate line toward the sides of the furnace whereby the fuel and solid products of combustion are fed by gravity from an intermediate portion toward the 40 sides of the furnace, and means for feeding fuel to said twyers at said intermediate line and at a plurality of positions on the declivities on both sides of said intermediate line.

8. In an underfeed stoker, a plurality of twyers successively decreasing in elevation from an intermediate line toward the sides of the furnace whereby the fuel and solid products of combustion are fed by gravity 50 from an intermediate portion toward the sides of the furnace, fuel retorts or troughs at said intermediate line and of progressively decreasing cross section on each side of said intermediate line, and means for feeding fuel through said retorts or troughs. 55

9. In an underfeed stoker, a plurality of twyers successively decreasing in elevation from an intermediate line toward the sides of the furnace whereby the fuel and solid products of combustion are fed by gravity 60 from an intermediate portion toward the sides of the furnace, fuel retorts or troughs at and on each side of said intermediate line, and fuel feeding devices successively 65 decreasing in capacity for feeding progres-

sively smaller quantities of fuel through the successive retorts or troughs.

10. In an underfeed stoker, a plurality of twyers successively decreasing in elevation from an intermediate line toward the 70 sides of the furnace whereby the fuel and solid products of combustion are fed by gravity from an intermediate portion toward the sides of the furnace, fuel retorts or troughs at and on each side of said intermediate line, and fuel feeding devices in the respective retorts or troughs operative to feed progressively smaller quantities of fuel. 75

11. In an underfeed stoker, a plurality of 80 twyers successively decreasing in elevation from an intermediate line toward the sides of the furnace whereby the fuel and solid products of combustion are fed by gravity from an intermediate portion toward the 85 sides of the furnace, means for feeding fuel to said twyers at and on each side of said intermediate line, and reciprocating grate bars on which the solid matter is delivered from the declivities of said twyers. 90

12. In an underfeed stoker, a plurality of twyers successively decreasing in elevation from an intermediate line toward the sides of the furnace whereby the fuel and solid products of combustion are fed by gravity 95 from an intermediate portion toward the sides of the furnace, means for feeding fuel to said twyers at and on each side of said intermediate line, and a grate, having a progressively decreasing air supply toward the 100 side of the furnace, on which the solid matter is delivered from each declivity of the twyers.

13. In an underfeed stoker, a plurality of twyers successively decreasing in elevation 105 from an intermediate line toward the sides of the furnace whereby the fuel and solid products of combustion are fed by gravity from an intermediate portion toward the sides of the furnace, means for feeding fuel 110 to said twyers at and on each side of said intermediate line, grate bars reciprocating transversely to the declivity of said twyers and on which the solid matter is delivered, and dumping grates at the outer sides of 115 said grate bars.

14. In an underfeed stoker, a plurality of twyers successively decreasing in elevation from an intermediate line toward the sides of the furnace whereby the fuel and solid 120 products of combustion are fed by gravity from an intermediate portion toward the sides of the furnace, means for supplying said twyers with air, said twyers having internal air-directing walls for directing the 125 incoming air into cooling contact with the heated surfaces of said twyers, and means for feeding fuel to said twyers at and on each side of said intermediate line.

15. In an underfeed stoker, a plurality of 130

5 twyers successively decreasing in elevation from an intermediate line toward the sides of the furnace whereby the fuel and solid products of combustion are fed by gravity from an intermediate portion toward the sides of the furnace, said twyers having external ash-collecting recesses, and means for feeding fuel to said twyers at and on each side of said intermediate line.

10 16. In an automatic underfeed stoker, a plurality of twyers successively decreasing in elevation from a medial line toward the sides of the furnace whereby the fuel and solid products of combustion are fed by gravity from the center to the sides of the furnace, fuel retorts or troughs between said twyers, and fuel feeding devices in said retorts or troughs for feeding progressively smaller quantities of fuel through the successive retorts or troughs on each side of said medial line.

15 17. In an automatic underfeed stoker, a plurality of twyers successively decreasing in elevation from a medial line toward the sides of the furnace whereby the fuel and solid products of combustion are fed by gravity from the center to the sides of the furnace, fuel retorts or troughs between said twyers, and fuel feeding devices in said retorts or troughs for feeding progressively smaller quantities of fuel through the successive members of successively decreasing capacity.

20 18. In an automatic underfeed stoker, a plurality of twyers successively decreasing in elevation from a medial line toward the sides of the furnace whereby the fuel and solid products of combustion are fed by gravity from the center to the sides of the furnace, fuel retorts or troughs between said twyers, and fuel pushers in said retorts or troughs, each comprising a fuel feeding ram and a member reciprocating therewith and having projections of successively decreasing height.

25 19. In an automatic underfeed stoker, a series of fuel supporting surfaces constituting twyers successively decreasing in elevation from a medial fore and aft line toward the sides of the furnace, fuel retorts or troughs between said twyers at and on both sides of said medial line, and means for feeding fuel through said retorts or troughs to said twyers.

20. In an underfeed stoker, a plurality of twyers successively decreasing in elevation from an intermediate line toward the sides of the furnace whereby the fuel and solid products of combustion are fed by gravity from an intermediate portion toward the sides of the furnace, said twyers having a corrugated surface, and means for feeding fuel to said twyers at and on each side of said intermediate line. 55

21. In an automatic underfeed stoker, a series of twyers providing fuel-supporting surfaces which are inclined laterally on each side of an intermediate fore and aft line, fuel retorts or troughs at each side of said fore and aft line and substantially parallel thereto for discharging fuel to said surfaces along a plurality of lines spaced in the direction of inclination of said surfaces, and means for feeding fuel through said retorts or troughs to said fuel-supporting surfaces. 60 70

22. In an automatic underfeed stoker, a series of twyers providing fuel-supporting surfaces which are inclined laterally on each side of an intermediate fore and aft line, fuel retorts or troughs between said twyers at each side of said fore and aft line and extending substantially parallel thereto, and means for feeding progressively smaller quantities of fuel through the retorts or troughs which succeed each other in the direction of decreasing elevation of said fuel- 80 85 surfaces. 75

23. In an automatic underfeed stoker, a series of twyers providing fuel-supporting surfaces which progressively differ in height on each side of an intermediate fore and aft line, a plurality of fuel retorts or troughs at each side of said fore and aft line and extending substantially parallel thereto, and means for feeding fuel through said retorts or troughs to said fuel-supporting surfaces, 90 95 said fuel-feeding means being of progressively decreasing capacity in successive retorts or troughs in the direction of downward inclination of the fuel-supporting surfaces. 100

In witness whereof I have hereunto set my hand this 27th day of February, 1914.

MAURICE RATEL.
